[57] CLAIM

The ornamental design for a shovel attachment for an ice axe, as shown and described.

DESCRIPTION

FIG. 1 is a bottom perspective view of a shovel attachment for an ice axe, showing my new design;

FIG. 2 is a top perspective view thereof;

FIG. 3 is a side view thereof, the opposite side being of identical appearance;

FIG. 4 is a rear view thereof;

FIG. 5 is a front view thereof;

FIG. 6 is a bottom perspective view of an alternative embodiment thereof; and,

FIG. 7 is a rear elevational view of said alternative embodiment.
